UNITED STATES PATENT OFFICE.

JAMES M. STRYKER, OF CHICAGO, ILLINOIS, ASSIGNOR TO M. S. INGRAHAM,
OF SAME PLACE.

BUTLER'S KNIFE.

SPECIFICATION forming part of Letters Patent No. 683,867, dated October 1, 1901.

Application filed May 28, 1900. Serial No. 18,192. (No model.)

To all whom it may concern:

Be it known that I, JAMES M. STRYKER, a citizen of the United States, residing at Chicago, county of Cook, State of Illinois, have 5 invented certain new and useful Improvements in Butlers' Knives, which are fully set forth in the following specification, reference being had to the accompanying drawings, forming a part thereof.

10 The purpose of this invention is to provide an improved knife adapted for the purpose of scraping and cleaning plates, dishes, and cooking utensils.

In the drawings, Figure 1 is a plan or side 15 elevation of my improved knife. Fig. 2 is a detail section, on an exaggerated scale, at the line 2 2 on Fig. 1. Figs. 3, 4, and 5 are perspectives showing different forms of vessels, showing the manner of using my improved 20 knife therewith.

My improvement comprises a blade A, of 25 spring sheet metal, and a handle B, preferably of wire or rod bent into suitable form to receive the blade, as illustrated.

25 The utility of this device arises largely out of the shape of the blade and secondarily out of its relation to the handle. The blade A is made, as stated, of stiff sheet metal and is shaped so as to have the outer end edge a³ 30 merging in convexly-rounded outer end corners A² and A³ and upper and lower side edges, the former comprising portions a⁴ and a⁵ and an intermediate reentrant curve A⁴ and the latter comprising portions a⁵ and a⁶, 35 an intermediate convexly-rounded corner A', and reentrant curve A⁵, the portions a⁵ and a⁶ of the upper and lower side edges, respectively, running back from the concave reentrant curves A⁴ and A⁵, being convergent and 40 constituting the stem a⁷ of the blade, adapted to be received by the handle and affording means for attaching the latter. The angle between the portions a⁴ and a⁵ of the lower side edge, in which the outline of the convex 45 corner A' merges, is an obtuse angle—that is, the extreme tangents to the curve of this corner, if produced toward each other, would meet in an obtuse angle, as at x. The line of the edge a⁵ between the corners A² and A³, 50 if produced to meet the line of the portion a² of the lower side edge, would form therewith

a slight acute angle at y. The portion a' of the upper side edge between the corner A³ and reentrant curve A⁴, if produced in a straight line to meet the end edge a⁸, would 55 form therewith an angle at z more acute than the angle y. The handle extends from the stem a⁷ of the blade in a direction which for a short distance is substantially in the direction of the portion a⁵ of the upper side edge. 60 I prefer to form the handle B, as illustrated, of a single piece of wire folded upon itself at substantially the middle point b, one limb b' being straight and the other being bent at b³, 65 so as to diverge from the limb b', the end portions of the two limbs thus conforming in relative direction to the angle between the directions of the portions a⁵ and a⁶ of the upper and lower side edges, respectively, of the blade. The end portions B' and B² of the 70 two limbs are provided at the inner side with saw cuts or slots B³ B³ of suitable width to receive the said edges of the blade, the lips of the slotted wire forming the margins of the slots being designed to be clenched down by 75 a heavy blow or pressure in a die-press onto the surfaces of the blade and thus secured thereto. For greater security in respect to the fastening of the handle to the blade I form at the rear end of the stem a⁷ a recess or deep 80 notch a⁸, leaving standing projections A⁹ A⁹ facing each other, whose width is substantially equal to the depth of the saw-cuts B³ B³ in the wire forming the handle, and in the inner or facing edges of said projections— 85 that is, in the lateral edges of said notch—I form small notches a⁹ a⁹, which will be overhung by the lips or lateral margins of the slots B³ B³, and when the blow or pressure is applied for the purpose of clenching said 90 lips onto the blade some portion of the metal of the wire will be sunk into the notches a⁹. The position of the notches being on the inner side of projections on the outer side of which the wire handles are applied, causes 95 the engagement of the metal sunk into these notches, without regard to the form of the notches, to prevent the detachment of the handle either by endwise pull or outward movement, such as might be caused by springing the two limbs of the wire handle. Thus 100 a very secure form of attachment is made

which is not dependent for its permanency upon the form of the notches, as is the case when engagement is effected by sinking metal into dovetailed notches in the outer edges 5 of the blade, as in constructions heretofore in use.

The mode of use of this tool is illustrated in the drawings, the angles A' , A^2 , and A^3 being adapted by inclining the blade at varying angles to fit the common curves of dishes, plates, cups, and cooking utensils, the elasticity of the metal of which the blade is composed making it possible to produce an almost perfect fit by slight pressure, while the 10 adjacent edges a^2 and a^3 fit the plane surfaces of the vessel being cleaned, and thus the tool is adapted to scrape quickly and easily all the surfaces, plane and curved. The angle of the edge at a^3 to the general extent of 15 the handle B is such as to adapt the knife for the most natural and easiest movement in scraping extended plane surfaces—as the inner surfaces of plates, platters, saucers, and the like—the said angle being such as to enable a forward and lateral pushing motion 20 of the blade, as shown in Fig. 3, without in any way perceptibly lessening the efficiency of said edge when the knife is used perpendicularly, or, more effectively, in an approximate 25 perpendicular position in cleaning the lower interior surfaces of frying-pans, kettles, basins, and other deep utensils, as shown at a in Fig. 4. The angles between the portion 30 a^2 of the lower side edge and the end edge a^3 and between said end edge a^3 and the portion a^4 of the upper side edge are such as to adapt the knife for use in cleaning the concave curves of plates and like vessels 35 with a motion either from right to left or from left to right without turning over (and 40 the accompanying necessity of previously cleaning) the blade by causing the round corners A^2 A^3 (this enabled by the reentrant curve A^4) to follow around the marginal 45 curve of the plate when the edge a^3 is kept in contact with the plane central surface at an apparently acute angle to the direction in which it is advanced, as will be also seen in Fig. 3. The angle of the portion a^2 of the 50 lower side edge to the general extent of the handle B and the effect of said handle from said blade are such as will enable said portion a^2 to be used, if desired, on larger plane surfaces, such as platters and the like, and in 55 cleaning the interior walls of kettles, basins, and other deep utensils, as shown at a in Fig. 5.

I claim—

1. A butler's knife for cleaning dishes and 60 cooking utensils, consisting of a single flexibly-elastic blade having convex corners, A' and A^2 , the former inscribed within a widely-obtuse angle and the latter inscribed within a slightly-acute angle, and a straight edge between 65 said rounded corners; in combination with a handle extending rigidly from the end

beyond said obtuse angle, and secured along the edge running from said angle to said end, and beyond said end offset from the line of the straight edge. 70

2. A knife for the purpose described, consisting of a flexibly-elastic blade having the convex corner A^3 inscribed within an acute angle, and the reentrant curve, A^4 , in combination with a handle extending rigidly from the end opposite said convex corner in a direction substantially tangent to said reentrant curve, and secured to said edge from the deepest point of the curve to the remote end; whereby said knife is stiffened and reinforced at said edge, and the said rounded corner constitutes a flexibly-elastic projection offset laterally from the line of the handle. 75 80

3. A knife for the purpose stated, consisting of a single flexibly-elastic blade having a straight edge, a^3 , at one end, in combination with a handle extending rigidly from the opposite end in a direction slightly oblique to such blade; said straight edge merging at 90 both ends in rounded corners each inscribed within an acute angle, such rounded corners merging in the lateral edges of the blade, such lateral edges extending convergently from the rounded corners toward the handle, 95 and being also convergent along the extreme portions of the said edges, the handle secured along said extreme portions of the lateral edges to stiffen the blade at the end portion opposite the straight edge; whereby 100 both said rounded corners constitute projections extending laterally beyond the remaining lateral outline of both the blade and handle and the knife is provided with a straight edge transverse to the length of the handle. 105

4. A knife for the purpose stated, consisting of a single flexibly-elastic blade having a straight edge, a^3 at one end; in combination with a handle extending rigidly from the opposite end, said straight edge merging at both 110 ends in rounded corners inscribed within acute angles and merging in converging portions of the lateral edges of the blade, the handle being secured to the extreme portions of the lateral edges to stiffen the blade at the 115 end portion opposite said straight edge.

5. A knife for the purpose described, consisting of a single flexibly-elastic blade having at one end rounded corners each inscribed within an acute angle, the edges converging 120 from said acute angles having reentrant curves toward the opposite end of the blade, in combination with a handle joined to said opposite end at the edges of the blade running from said reentrant curve toward said 125 end, whereby that end of the blade is stiffened or reinforced, and the remaining flexible portion is offset laterally both ways from the trend of the handle.

6. In combination with the blade having at 130 the rear end the recess a^3 , forming endwise projections, A^9 , continuing the lateral edges

of the blade, the inner or facing edges of said projections having notches, a^9 ; a handle made of wire bent to form two limbs and longitudinally slotted on the inner side of the ends 5 of said limbs respectively such handle being applied to the blade by entering the lateral marginal portions of the blade including said projections A^9 in said longitudinal slots respectively to such depth that the lips of the 10 slots overhang the notches a^9 , said handle being secured to the blade by the metal of the

handle being pinched onto the surface of the blade and sunken into said notches a^9 .

In testimony whereof I have hereunto set my hand, at Chicago, Illinois, in the presence 15 of two witnesses, this 23d day of May, A. D. 1900.

JAMES M. STRYKER.

In presence of—

CHAS. S. BURTON,
EDGAR L. CONANT.
